CONTACT DEVICE FOR SWITCHES.

931,911.

Specification of Letters Patent. Patented Aug. 24, 1909.

Application filed May 18, 1908. Serial No. 423,406.

To all whom it may concern:

Be it known that I, JOHN A. YORK, a citizen of the United States, and a resident of Hartford, in the county of Hartford and 5 State of Connecticut, have invented certain new and useful Improvements in Contact Devices for Switches, of which the following is a full, clear, and exact description.

The invention relates to snap electric 10 switches, and particularly to the construction and mounting of the movable contacts or pole plates of rotary and push switches.

The object of the invention is to provide a pole plate and a mounting therefor, which 15 is equally applicable to either single or multiple pole switches of both the rotary and push type, the form and construction of which is such that it may be utilized in various positions with respect to the actuating 20 mechanism to provide the necessary movable contacts for the various types of switches, without altering the construction of the plate and mounting for the several types of switches with which they are used.

25 While the pole plate and mounting therefor, which form the subject of this invention, are applicable, without change, to the actuating mechanism of either a rotatory snap or push snap electric switch, the invention is illustrated herein only as applied to the actuating mechanism of a rotary snap switch.

Figure 1 is a plan view of a rotary snap switch mechanism provided with a pole plate 35 and mounting constructed according to this invention. Fig. 2 shows a central vertical section of the same, on the plane indicated by the dotted line *a—a* on Fig. 1. Fig. 3 shows on larger scale, a section on the plane indicated by the dotted line *b—b* on Fig. 1. Fig. 4 shows a plan of the pole carrying or spring plate. Fig. 5 shows an edge view of the same. Fig. 6 shows a plan of one form of movable contact or pole plate in full lines, 45 and shows in dotted lines the same plate or another plate arranged in reverse position, as the plates lie in a double pole switch. Fig. 7 shows an edge view of the plates shown in Fig. 6. Fig. 8 shows a plan of an 50 insulating piece that may be used for separating the movable contacts or pole plates when arranged as indicated in Figs. 6 and 7.

The base 1 of the switch illustrated in the drawings, is formed of insulating ma-

terial, such as porcelain, and has a centrally arranged spindle 2 provided with a button 3, by means of which the spindle may be rotated and the actuating mechanism operated. The spiral spring 5 has one end connected with the spring plate 4, and the other end with the handle 3, in the usual manner, so that turning the handle puts the spring under tension, and at the proper time throws the spring plate which carries the movable contacts or pole plates. As the actuating mechanism and locking and release mechanism form no part of the present invention, they are not illustrated and described in detail. Any common form of actuating and locking mechanism may be used.

The spring plate 4, which is shown, has a central hub 7 through which the spindle extends, and about which the spiral spring is coiled. This plate is shown as provided 75 with lugs 8 and 9, which are bent up from the edges of the plate for the purpose of supporting the pole plates. These lugs extend at right angles from diametrically opposite sides of the center of rotation and have 80 shoulders 10 which form a rest for the pole plates and the insulation therefor.

The switch illustrated in the drawings has two pole plates 6 and 14, which pole plates have the same configuration. Each pole 85 plate has contacting or brush ends 23 and 24, which are offset from and extend in a plane parallel with the plane of the body of the pole plate. In the center of each plate is a circular opening 26, connecting with 90 which are openings 27 and 28. These openings are arranged so that the axis or greatest length of the space in the body of the plate, extends at an angle of substantially 45 degrees with the longitudinal axis of the pole 95 plate, as shown in Fig. 6. As a result of this construction, when two pole plates are placed together with the longitudinal axes the same, or with the longitudinal axes at right angles, the openings in the plates coincide, as indicated in Fig. 6. When a double pole switch, such as is shown in the drawings, is made up with pole plates having this construction, it is preferred to first place a metallic plate 11 on the lugs 8 so as to 100 rest upon the shoulders 10. This plate is insulated from the adjacent parts by a washer 12 of insulating material and is insulated 105

from the lower pole plate 14 by a washer 13 of insulating material. The brush ends of the lower pole plate mounted in this manner are in such a plane that when the switch is operated, those ends make and break connection between the terminals or fixed contacts 17 and 18.

Above the pole plate 14 is a washer 19 of insulating material. The pole plate 6 above the washer 19 is identically the same form as the pole plate 14, but is placed in a reverse position so that the axes of the two plates extend at right angles with each other. Above the pole plate 6 is an insulating washer 21 and above this is arranged a metallic plate 22, which preferably has the same form as the bottom plate 11. Insulating pieces 16 of the shape shown in Fig. 8 are placed in the openings in the pole plates 6 and 14 to insulate these pole plates from the supporting lugs. When the parts are

assembled, the ends of the stud 8 are headed over to secure them together.

The invention claimed is:

In an electric switch in combination with 25 the actuating mechanism, a spring plate, two supports projecting from said plate at right angles thereto, a pole plate with brush ends extending outwardly therefrom, said pole plate having an elongated opening, the longitudinal axis of which extends at an angle of substantially forty-five degrees with the longitudinal axis of the pole plate, and insulation mounted on said supports and located in the ends of said opening on opposite 35 sides of the longitudinal axis of the pole plate.

JOHN A. YORK.
